UNITED STATES PATENT OFFICE.

RUSSEL G. WOODWARD, OF WAUKEGAN, ILLINOIS, ASSIGNOR TO UNION SPECIAL SEWING MACHINE COMPANY, OF CHICAGO, ILLINOIS, A CORPORATION OF ILLINOIS.

OVERSEAMING SEWING-MACHINE.

1,097,280.

Specification of Letters Patent. Patented May 19, 1914.

Application filed April 8, 1901. Serial No. 54,897.

To all whom it may concern:

Be it known that I, RUSSEL G. WOODWARD, a citizen of the United States, residing at Waukegan, in the county of Lake, State of Illinois, have invented certain new and useful Improvements in Overseaming Sewing-Machines, of which the following is a description, reference being had to the accompanying drawing and to the letters and figures of reference marked thereon.

My invention relates to an improvement in sewing machines and has been designed particularly for use in making bags, the object being to provide a machine which will practically work at high speed upon very coarse, cheap and heavy material and with very coarse and gritty thread, as well as with the finer qualities of material and thread.

The stitch forming mechanism herein shown, comprises a vertically reciprocating needle which passes down through the material and throws out a loop of thread below the throat plate, a spreader takes the loop of needle thread, draws it to one side and to a point above the plane of the throat plate, when a swinging looper carries its thread through the needle loop thus held on the spreader, and into position so that the needle passes down through the looper loop, the spreader meanwhile releasing the needle loop in its passage downwardly to take the needle thread again. The looper and spreader are supported above the cloth plate and the mechanisms for supporting and operating the same are very simple, durable and capable of high speed.

The invention consists primarily of a sewing machine having a reciprocating needle, a rocking spreader supported above the cloth plate and reciprocating from a point above to a point below the cloth plate, where it seizes the needle thread and draws the loop to a point above and to one side the throat plate, and a looper supported and oscillating entirely above the bed plate and carrying its thread through the needle loop and into position to be engaged by the needle in its descent.

Secondly, the invention consists in the details of construction of the support and

operating mechanism of the spreader and in various combinations of parts, all as hereinafter described and referred to in the appended claims.

The invention is illustrated in the accompany drawings, in which—

Figure 1 is a front view, partially broken away, of a sewing machine embodying my invention; Fig. 2 is a rear view; Fig. 3 is an end view; Fig. 4 is a front perspective view of the spreader supporting arm and shaft, this figure representing the position of the parts as the looper is about to carry its thread into the loop of needle thread held in the spreader. Fig. 5 is a detail view, representing the position of the parts as the needle is about to pass into the looper loop and the spreader is about to release the needle loop. Fig. 6 is a perspective view of the under side of the throat plate; Fig. 7 is a top plan view of the same; Fig. 8 is a longitudinal side elevation of the throat plate; Fig. 9 is a detail perspective view, showing the relation of the needle guard on the spreader and the needle guard on the throat plate, to the needle when in its lower position; Fig. 10 is a front plan view of the needle and spreader, when in the highest position; Fig. 11 is a view similar to Fig. 10, with the needle and spreader in their lowest position. Fig. 12 is a detail in plan showing the spreader detached from its support.

In these drawings, the machine shown is of the well known Union Special type, having the vertically reciprocating needle bar A, the presser foot B, the feeding mechanism (not shown) all of which parts are of well known construction and need not be herein specifically referred to. The needle bar A supports the thread carrying eye pointed needle a which passes down through the presser foot and throat plate and in its upward movement throws out a loop of thread in the usual manner.

Mounted in bearings in a bracket C attached to or formed integral with the head of the machine, is a shaft D, extending transversely of the machine frame, and having mounted or clamped on its forward end a

bell crank lever, one arm E of which extends toward the right of the machine and is provided on its end with a socket b for the reception of the shank of the spreader, 5 to be hereinafter referred to. The other arm F of this bell crank lever extends upwardly and is provided with a crank pin or projecting ball stud G from which connection is made to the needle lever H by the pitman rod I. The spreader K is of the form 10 shown and moves up and down in the arc of a circle from a point below and back of the needle to a point to one side the needle and above the cloth plate, and has on its 15 lower end a hook or beak c, which, as the spreader moves from low to high position, catches the needle loop and draws it to one side and in position to allow the looper with its thread to pass into the needle loop on the 20 spreader.

It will be seen that the oscillation of the spreader is accomplished through the movement of the needle lever. The spreader K has a needle guard plate or projection d adjacent its lower end, which co-acts with a guard e on the under side of the throat plate to guide the needle and prevent its deflection. The projection d on the thread-manipulating device, as above noted, forms 25 a needle guard, and the outer face of this needle guard is substantially in the same plane as the outer face of the beak of the loop-engaging device, so that the needle is positioned by the needle guard for the passing 30 of the beak by the needle. The looper L carries a thread, is arranged on an oscillating axis and works entirely above the bed plate of the machine, the needle passing down between the part d on the spreader, 35 and the part e on the throat plate, thus preventing the springing of the needle which might otherwise take place. Its supporting 40 shaft M is mounted in bearings in the machine frame and is oscillated by pitman, lever, and eccentric connections to the driving 45 shaft N, as shown in Fig. 2.

The particular mechanism for operating the looper as well as the looper itself, form no part of the present invention, except in 50 so far as the arrangement and co-operation with the spreader and needle are novel.

Suppose the needle to be in its lowest position, the spreader is also in its lowest position and the looper has not yet reached 55 its retracted position. As the needle moves up it throws out a loop, the spreader moves back and the beak or hook c catches the needle loop. As the spreader and needle recede, the spreader draws the needle loop to 60 the right and raises it above the throat plate; the looper moves forward and enters the loop of needle thread, carrying its own thread therethrough, and passes around in front of the needle so that the needle in its 65 descent will catch the looper loop. When

it has caught the looper loop, the spreader in its descent will release the needle loop and the same will be drawn up to the edge of the goods, making the proper finish for the material. It will be noted that as the 70 needle moves down, the guard e on the throat plate prevents the needle from being deflected away from the spreader, which passes on the opposite side of the needle. The guard d on the lower edge of 75 the spreader also moves into co-operative relation to the needle in advance of the beak of the spreader engaging the needle loop, and consequently the needle guard d on one side of the needle, and the needle guard e 80 on the other side of the needle holds said needle in proper position for the spreader beak to pass the needle and enter the needle loop.

Various minor modifications and changes 85 in the construction of the parts of this device may be made, without departing from the spirit of my invention.

Having thus described my invention, what I claim as new, and desire to secure by Letters Patent, is:—

1. In an overseaming machine, a stitch-forming mechanism including a reciprocating needle, a spreader supported above the cloth plate, with means for oscillating it to cause it to take a loop of needle thread from below the cloth plate and carry it into position above the same, a looper, a shaft arranged above the cloth plate supporting said looper, said shaft being inclined from the vertical, with means for oscillating said shaft to cause the looper to pass from a point in rear to a point in front of the needle and carry its thread through the needle loop on the spreader into position to be engaged by the needle in its descent; substantially as described.

2. An overseaming machine, comprising in combination, a work support, a stitch-forming mechanism including a reciprocating needle bar, a needle carried thereby, a thread-manipulating device pivotally supported above the work support and moving in a plane substantially at right angles to the line of feed and co-operating with the needle below said work support, means for oscillating said thread-manipulating device, a shaft arranged above the work support adjacent the needle bar, said shaft being inclined to the needle bar, means for oscillating said shaft, a thread-manipulating member carried by said shaft and moving in a plane inclined to the work support and across the plane of movement of the first named thread-manipulating device and co-operating with said first named thread-manipulating device and needle to form an over-edge stitch; substantially as described.

3. An overseaming machine, comprising in combination, a work support, a stitch-

forming mechanism including a reciprocating needle bar, a needle carried thereby, a thread-manipulating device pivotally supported above the work support at one side 5 of the needle, and coöperating with the needle below the work support, said thread-manipulating device comprising an arm extending across the line of seam and a thread-engaging member carried by said arm and 10 curved substantially in an arc with the pivot of the thread-manipulating device as a center, said thread-engaging member having a loop-engaging hook extending backward substantially parallel to the body of said 15 thread-engaging member, and a thread-manipulating device pivoted above the work support to swing about an axis inclined to the needle bar, said last named thread-manipulating device moving in a plane inclined 20 to the work support and across the plane of movement of the thread-manipulating device, and coöperating with said first named thread-manipulating device and needle to form an over-edge stitch; substantially as 25 described.

4. A sewing machine including in combination a needle and complementary stitch forming mechanism, including a thread manipulating device, having a loop engaging 30 beak, a supporting shank therefor, said beak being laterally offset from said shank and a needle guard carried by and projecting from said shank in advance of said beak, the outer face of said needle guard 35 being substantially in the same plane as the outer face of said beak, whereby said needle is positioned for the passing of said beak by said needle.

5. A sewing machine including in combination, a work support, a needle and complementary stitch forming mechanism, including a thread manipulating device having a loop engaging beak, a supporting shank for said beak, pivoted above the work support, 40 a needle guard carried by said shank, said guard being located in advance of said beak and at a greater distance from the pivotal center of said support than said beak, whereby said beak will coöperate with said 45 needle above the eye thereof, and said guard will coöperate with said needle below said eye.

6. A sewing machine including in combination, a work support, a needle, a thread carrying implement pivoted above said work support and having a beak coöperating with 50 said needle below said work support, a second thread carrying implement coöperating with said first named implement and with 55 said needle above the work support and a needle guard carried by and moving with said first named thread carrying implement, said needle guard coöperating with said needle, below the eye thereof.

65 7. In an overseaming machine a cloth

plate, stitch forming mechanism, including a reciprocating needle, a spreader with means for oscillating it to cause it to take a loop of needle thread from below the cloth plate, and carry it into position above the same, 70 and a looper with means for operating it to cause it to carry its thread through the needle loop on the spreader, into position to be engaged by the needle in its descent, said spreader being provided with a needle guiding plate whereby springing of the needle is prevented; substantially as described. 75

8. In an overseaming machine a cloth plate, stitch forming mechanism including a reciprocating needle, a spreader with means for oscillating it to cause it to take a loop of needle thread from below the cloth plate, and carry it into position above the same, and a looper with means for operating it, to cause it to carry its thread through the needle loop on the spreader into position to be engaged by the needle in its descent, said spreader being provided with a needle guiding plate, and a guard plate or member on the throat plate between which and the 80 projection on the spreader, the needle is guided, whereby springing of the needle is prevented. 85

9. An overseaming machine, comprising in combination, a work support, a needle 95 bar, a needle carried thereby, a shaft arranged above the work support and inclined to said needle bar, a thread-carrying implement carried by the lower end of said shaft, an arm pivotally supported above the work support and vibrating in a plane between the needle bar and said shaft, and a thread-manipulating implement carried by said 100 arm and coöperating with said needle and said first named thread-carrying implement 105 to form an overedge stitch.

10. An overseaming machine, comprising in combination, a work support, a needle bar, a needle carried thereby, a shaft arranged above the work support and adjacent the needle bar, a thread-carrying implement carried by the lower end of said shaft, an arm pivotally supported above the work support and vibrating in a plane between the needle bar and said shaft, and a thread-manipulating implement carried by said arm 110 and coöperating with said needle and said first named thread-carrying implement to form an overedge stitch, means for vibrating said arm, including a link operating in 115 front of said needle bar.

11. An overseaming machine comprising in combination a work support, a needle bar, a needle carried by said needle bar, a shaft arranged above the work support and 120 adjacent the needle bar, a thread carrying implement mounted on the lower end of said shaft and coöperating with the needle above the work support, a thread manipulating implement coöperating with the needle be- 125

130

neath the work support and with said thread carrying implement above the work support, said shaft being so disposed that the implement carried thereby moves in a plane
5 slightly inclined to the work support from a point in rear of the thread manipulating implement to a point in front of said needle.

In testimony whereof I affix my signature, in presence of two witnesses.
